(57) **CLAIM**

The ornamental design for an assembly of oral-care components, as shown and described.

DESCRIPTION

FIG. 1 is a top-front-left perspective view of an assembly of oral-care components in an exploded configuration showing my new design;

FIG. 2 is a bottom-rear-right perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is an enlarged top plan view thereof;

FIG. 8 is an enlarged bottom plan view thereof;

FIG. 9 is a top-front-left perspective view of an assembly of oral-care components in a collapsed configuration showing my new design;

FIG. 10 is a front elevational view thereof;

FIG. 11 is a rear elevational view thereof;

FIG. 12 is a left elevational view thereof;

FIG. 13 is a right elevational view thereof;

FIG. 14 is an enlarged top plan view thereof; and,

FIG. 15 is an enlarged bottom plan view thereof.

The broken lines showing an interchangeable toothbrush in FIGS. 1 through 8 are included for the purpose of illustrating environmental structure and form no part of the claimed design.

1 Claim, 15 Drawing Sheets
